US00D918615S

(12) **United States Design Patent** (10) Patent No.: **US D918,615 S**
(45) Date of Patent: **** May 11, 2021**

(54) **PAPER DISPENSER**

(71) Applicant: **CASCADES CANADA ULC**,
Montreal (CA)

(72) Inventors: **Benoit Orban**, Saint-Lambert (CA);
Mélody Sue Myette, Montreal (CA)

(73) Assignee: **CASCADES CANADA ULC**,
Montreal (CA)

(**) Term: **15 Years**

(21) Appl. No.: **29/659,946**

(22) Filed: **Aug. 14, 2018**

(30) **Foreign Application Priority Data**

May 29, 2018 (CA) ..... CA 181664

(51) LOC (13) Cl. **23-02**

(52) U.S. Cl. **D6/523**
USPC .....

(57) **CLAIM**

The ornamental design for a paper dispenser, as shown and described.

DESCRIPTION

FIG. 1 is a perspective view of a paper dispenser;
FIG. 2 is a front elevation view of the paper dispenser shown in FIG. 1;
FIG. 3 is a rear elevation view of the paper dispenser shown in FIG. 1;
FIG. 4 is left-side elevation view of the paper dispenser shown in FIG. 1;
FIG. 5 is right-side elevation view of the paper dispenser shown in FIG. 1;
FIG. 6 is a top plan view of the paper dispenser shown in FIG. 1; and,
FIG. 7 is a bottom plan view of the paper dispenser shown in FIG. 1.
The broken lines shown in the figures represent portions of the paper dispenser that form no part of the claimed design.

1 Claim, 7 Drawing Sheets
